US00D590387S

(12) **United States Design Patent**
Chen

(10) **Patent No.:** **US D590,387 S**
(45) **Date of Patent:** **** Apr. 14, 2009**

(54) **KIOSK**

(75) Inventor: **Ion C. Chen**, Laguna Hills, CA (US)

(73) Assignee: **Innova Electronics Corporation**,
Fountain Valley, CA (US)

(**) Term: **14 Years**

(21) Appl. No.: **29/291,766**

(22) Filed: **Sep. 13, 2007**

(51) **LOC (9) Cl.** **14-02**

(52) **U.S. Cl.** **D14/307**

(58) **Field of Classification Search** D14/302-307,
D14/130, 146, 371, 900, 127, 129; D13/163;
